(57) CLAIM

The ornamental design for a golf glove and ball marker caddy, as shown and described.

DESCRIPTION

FIG. 1 is a front perspective view of a golf glove and ball marker caddy showing our new design;

FIG. 2 is a front perspective view on an enlarged scale thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing of a belt and golf glove in FIG. 1 and the showing of a specific spring clip in all the figures are for illustrative purposes and form no part of the claimed design.
